UNITED STATES PATENT OFFICE.

SIDNEY W. WINSLOW, JR., OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE FOR USE IN THE MANUFACTURE OF BOOTS AND SHOES.

1,296,894.

Specification of Letters Patent.

Patented Mar. 11, 1919.

Application filed April 5, 1917, Serial No. 159,931. Renewed December 11, 1917. Serial No. 206,675.

To all whom it may concern:

Be it known that I, SIDNEY W. WINSLOW, Jr., a citizen of the United States, residing at Beverly, in the county of Essex and State 5 of Massachusetts, have invented certain Improvements in Soles for Use in the Manufacture of Boots and Shoes, of which the following description, in connection with the accompanying drawings, is a specification, 10 like reference characters on the drawings indicating like parts in the several figures.

This invention relates to improvements in soles for use in the manufacture of boots and shoes and is more particularly applicable to 15 the production of soles such as are used principally in the manufacture of turn shoes.

As is well known to those skilled in the art, it is necessary in making turn shoes 20 to provide the sole with suitable means for receiving and holding the single faced stitches which are used in attaching the shoe upper directly to the sole, this means usually being a marginal shoulder and a channel 25 formed in the upper surface of the sole. While it has been deemed desirable to use vulcanized rubber compound soles in making turn shoes, the fact that these soles are not adapted to the ordinary methods of preparation 30 to enable the shoe upper to be attached to the sole by single faced stitches has presented problems which have greatly retarded the manufacture of rubber sole turn shoes.

The principal object of the present invention 35 is to produce an improved vulcanized rubber compound turn sole the use of which will enable an attractive and serviceable rubber sole turn shoe to be manufactured with the same facility and under the same general 40 shoe factory conditions as a leather sole turn shoe.

With this object in view the invention contemplates the manufacture of a rubber sole for a turn shoe comprising a vulcanized 45 rubber compound body having a stitch receiving structure on its upper side consisting of fabric. A fabric sewing rib on a rubber compound sole, as distinguished from a rubber core, fabric-covered sewing rib, is 50 a novel feature and is an important advance in the art of making shoes for reasons that will hereinafter fully appear. In the illustrated embodiment of the invention the stitch receiving structure or sewing rib is

formed by a fabric member connected by 55 vulcanization with the rubber compound body with a portion extending substantially longitudinally of the member and raised relatively to laterally adjacent portions of the sole to constitute a stitch receiving and 60 holding rib. This fabric member of which the stitch receiving structure is a part is preferably a firm woven textile material, for example heavy canvas, and by so relating this fabric member with the body that a portion 65 of the fabric projecting above the rubber body of the sole constitutes the sewing rib a substantially all-fabric and non-stretchable sewing rib is provided for the attachment of the shoe upper. A stitch receiving rib having these characteristics is of importance in the production of a satisfactory rubber turn sole since it greatly facilitates the sewing operation and enables a tight and strong seam to be made and contributes to the production of a shoe that will 70 hold its shape during wear.

In the illustrated embodiment of the invention, the stitch receiving structure of the sole is formed by the upstanding marginal 80 edge or hem of a layer of textile fabric which is connected by vulcanization with the rubber compound body. Preferably the layer of fabric has its edge folded back on the body to produce a wide hem formed into an 85 upstanding edge which, in the completed sole, projects upwardly above laterally adjacent portions of the body so as to constitute a substantially all-fabric sewing rib. Conveniently, and as herein shown, the textile 90 fabric layer is incorporated in or assembled between layers of the rubber compound body before vulcanization and the sole then molded and vulcanized, the molding pressure causing a complete union to be 95 produced during vulcanization between the fabric and the rubber compound of the sole. Preferably, also, the molds are suitably shaped to form the portions of the body which are laterally adjacent to the stitch receiving rib so as to offer sufficient striking 100 shoulder for a curved needle at the base of the rib without weakening its connection to the body of the sole and to provide a well-defined angle along the feather of the sole 105 into which the upper may be tightly drawn.

Other objects and features of the invention will be apparent from the following de-

scription when considered in connection with the accompanying drawing and the invention will be pointed out in the appended claims.

5 In the drawings:—

Figure 1 is a perspective view, partly in section, of a shoe produced by the use of a sole of the present invention.

10 Fig. 2 is an enlarged section illustrating one manner in which the sole of the present invention may be produced.

Fig. 3 is a fragmentary perspective of the preferred embodiment of the sole of the invention.

15 In the illustrated embodiment of the invention a sole shaped blank 2 of "green" or unvulcanized rubber compound having sufficient thickness to offer a firm and serviceable wearing bottom for a shoe is first provided, 20 together with a strip 4 of green rubber corresponding in width to the width of the feather of the sole and of a length to extend completely around the sole. The stitch receiving structure for the sole consists of a 25 sheet of firm woven textile fabric 6 such, for example, as heavy canvas. The fabric layer may extend entirely across the sole from feather to feather and throughout its length, or alternatively it may be a strip of 30 suitable width to extend around the margin of the sole. The outer marginal portion 8 of this layer or strip 6 constitutes the stitch receiving rib for the sole and to this end it is preferably doubled over upon itself, as 35 illustrated in Figs. 2 and 3, a distance to provide a wide fold or hem the outer edge of which is turned up to project sufficiently above the upper surface of the sole to enable the shoe upper to be attached.

40 These sole parts 2, 4 and 6 are assembled in a two-part vulcanizing mold. The bottom mold 10 has a recess 11 shaped to receive the sole blank 2 and of a depth corresponding approximately to the thickness of the 45 sole to be made. The sole blank 2 is first placed in the mold 10 and the narrow rubber compound strip 4 laid on top of the blank 2 and against the wall of the recess. The hemmed folded marginal portion 8 of the 50 fabric member 6 is arranged in the mold on top of the blank 2 and against the inner sides of the strip 4 to present, at substantially right angles to the plane of the body portion, a stitch receiving rib 12. Another 55 blank 14 of green rubber compound, shaped to fit within the upturned flange of the fabric member 6, may next be placed in the mold as illustrated in Fig. 2. This layer of rubber builds up the middle part of the sole 60 and, in the vulcanizing process becomes united substantially integrally with the sole member 2, both members 2 and 14 being thereby united firmly to the fabric member 6. Also, the member 14 co-operates with the 65 strip member 4 to provide the proper lateral

support and backing for the upstanding stitch receiving rib 12. Experience has demonstrated that under the effect of heat and pressure during vulcanization, the rubber compound becomes so fluid as to penetrate readily through the fabric and bond it completely to the body portion of the sole, the fabric becoming well embedded in the rubber compound. The presence or absence, therefore, of the layer 14 or the thickness 75 of the said layer when used is of minor consequence in the broader aspect of this invention, because the rubber compound of the body 2 will, in the absence of a layer 14, sufficiently penetrate through the fabric 6 80 and form a coating on top of the fabric so that portions of the fabric lying below the plane of the top of the sole are vulcanized in the rubber compound in any case. After the different sole parts are assembled in position in the bottom mold 10, pressure is applied to the sole by the top mold 16, conveniently, as an incident to the vulcanization of the sole in a suitable vulcanizing apparatus. The bottom face of the mold 16 has 90 a recess 20 to receive the projecting fabric sewing rib 12 and the surfaces 22 of the mold laterally adjacent to the recess 20 are formed so as to provide the desired feather 24 extending around the margin of the sole and, 95 along the inside of the rib, to compress the material and provide sufficient clearance for the curved sewing needle used in attaching the shoe upper. A sufficient amount of rubber from the layer 14 or from the body 2 will 100 flow up on to the inside wall of the rib 12 when the sole is subjected to pressure to brace the rib and maintain it in stitch receiving relation to the sole. However, the surfaces 22 of the mold are formed so that the 105 rubber which flows up on to the inside wall of the rib is not sufficient in any way to be detrimental to the substantially all-fabric character of the rib. These surfaces 22 on the upper mold determine, to a large extent, 110 the amount of projection of the sewing rib 12 above the laterally adjacent portions of the sole and form a well-defined angle between the feather and the outer wall of the rib. This feature of the sole of the present 115 invention is of considerable advantage inasmuch as the shoe upper is drawn down into this angle when secured to the sole and it therefore defines the outline of the base of the upper. The vulcanization of the sole 120 effects an integral bonding and union of the several parts of the sole and imparts desired permanency of contour to the sole.

It will be noted that the portion of the fabric projecting above the upper surface 125 of the sole and constituting the stitch receiving rib 12 is strongly anchored in the rubber compound body and presents an exceedingly firm striking shoulder for the needle. A further and important feature 130

to be noted in the sole herein described resides in the fact that the material constituting the stitch receiving rib 12 for the sole is substantially all fibrous and non-compressible in which case the sewing needle penetrates it much more readily than if it were rubber and, because the fabric is substantially inextensible as compared with rubber, the upper may be drawn to the rib with a 5 tighter and stronger seam than when the rib is of rubber. By folding the fabric material 10 so that its outer edge is embedded in the rubber compound body, for example as illustrated, the two-walled stitch receiving rib 15 insures its accurate presentation for the sewing operation besides preventing the fraying out of the material particularly where it has been cut on the bias.

The sole of this invention may be employed in the same manner as a leather turn sole and under substantially the same shoe factory conditions, a shoe upper 30 being secured, in the first instance, to the sole by stitches received and held in the stitch receiving rib 12 of the sole and thereafter the 25 shoe turned right side out. The resulting shoe embodies all of the advantages of rubber sole shoes in general beside the recognized features of turn shoes.

30 The term rubber as herein used is not intended to be limited to a material the major part of which is rubber, but is used herein generically to include various rubber containing materials such as the so-called fiber soles now used extensively, as well as other similar materials.

Having described my invention, what I claim as new and desire to secure by Letters Patent of the United States is:—

40 1. As an article of manufacture, a rubber sole for turn shoes comprising a vulcanized rubber body having a stitch receiving structure on its upper side consisting of a fabric member embedded in the rubber compound 45 with a portion of the said fabric member projecting freely above the rubber body in a relation to present a stitch receiving rib raised relatively to laterally adjacent portions of the sole.

50 2. As an article of manufacture, a rubber sole for turn shoes comprising a vulcanized rubber compound body and a textile fabric member connected by vulcanization with the rubber body with its marginal portion independent of the rubber body and projecting 55 above laterally adjacent portions of the rubber body portion of the sole to form a stitch receiving rib on the upper side of the sole.

60 3. As an article of manufacture, a rubber sole for turn shoes comprising a rubber body having a stitch receiving rib formed on the upper side and consisting substantially wholly of fabric anchored to the rubber body by vulcanization.

4. As an article of manufacture, a rubber sole for turn shoes comprising a rubber body portion, and a fibrous layer extending transversely of the sole and secured to the upper side of the sole by vulcanization, the 70 marginal portion of said fibrous layer being molded to produce a portion projecting above laterally adjacent surfaces of the sole and constituting a substantially all-fibrous sewing rib.

75 5. As an article of manufacture, a rubber sole for turn shoes comprising a vulcanized rubber compound body and a fabric member anchored in the rubber compound and having a portion of the member unvulcanized to 80 the rubber body and projecting above laterally adjacent portions of the sole to form a stitch receiving and holding rib on the upper surface of the sole.

85 6. As an article of manufacture, a rubber sole for turn shoes comprising a vulcanized rubber compound body with a textile fabric member connected by vulcanization with the rubber body and having a marginal portion which is raised with relation to laterally adjacent portions of the sole and forms a substantially all-fabric stitch receiving rib.

90 7. As an article of manufacture, a rubber sole for turn shoes consisting of a rubber compound body with a textile fabric member connected by vulcanization with the rubber compound body, said fabric member having its marginal portion folded longitudinally and projecting above the rubber body to form a two-walled stitch receiving and 100 holding rib for the sole.

95 8. As an article of manufacture, a rubber sole for turn shoes consisting of a vulcanized rubber compound body and a fabric member connected by vulcanization with the 105 rubber compound body, said sole having a fabric stitch receiving and holding rib formed on its upper side by projecting a portion of the fabric member upwardly away from the rubber body to form a stitch 110 receiving rib.

115 9. As an article of manufacture, a rubber sole for turn shoes consisting of a vulcanized rubber compound body and a textile fabric member connected by vulcanization with the rubber compound body and having its marginal portion projecting above the rubber body and constituting a substantially all-fibrous non-compressible and non-stretchable 120 stitch receiving rib.

125 10. As an article of manufacture, a rubber sole for turn shoes consisting of a vulcanized rubber compound body and a textile fabric member connected by vulcanization with the rubber compound body and having its marginal portion projecting above the rubber body and constituting an all-fibrous and non-stretchable sewing rib.

130 11. As an article of manufacture, a rubber sole for turn shoes comprising a vulcanized

- rubber compound body and a layer of textile fabric embedded in the upper surface of the rubber compound body and having its marginal portion folded longitudinally on itself with the folded portion projecting above the upper face of the body at substantially right angles thereto and constituting a stitch receiving rib for single faced stitches.
- 10 12. As an article of manufacture, a vulcanized rubber compound turn sole provided with a textile fabric stitch receiving structure anchored along its base in the material of the sole and having its adjacent marginal portion offset from the sole to form a stitch receiving and holding rib.
13. As an article of manufacture, a sole for turn shoes comprising a rubber body and having a stitch receiving element raised from its upper side and comprising a fibrous member having its edges embedded in the rubber compound, and a portion between its edges projecting above laterally adjacent surfaces of the sole, said stitch receiving element being formed and arranged so as to provide a substantially all-fabric material in the path of the needle of the sewing machine when a shoe upper is attached to the said sole.

In testimony whereof I have signed my name to this specification.

SIDNEY W. WINSLOW, JR.
